UNITED STATES PATENT OFFICE.

OTTO E. F. HIMMIGHOEFER, OF ST. LOUIS, MISSOURI.

ELECTRIC ALARM-LOCK.

SPECIFICATION forming part of Letters Patent No. 739,272, dated September 15, 1903.

Application filed February 9, 1903. Serial No. 142,615. (No model.)

To all whom it may concern:

Be it known that I, OTTO E. F. HIMMIGHOEFER, a citizen of the United States, residing at St. Louis, State of Missouri, have invented certain new and useful Improvements in Electric Alarm-Locks, of which the following is a full, clear, and exact description, reference being had to the accompanying drawings, forming a part hereof.

10 My invention has relation to improvements in electric alarm-locks; and it consists in the novel arrangement and combination of parts more fully set forth in the specification and pointed out in the claims.

15 In the drawings, Figure 1 is a plan of the interior of an ordinary door-lock, showing my invention applied thereto, both bolts being in their locking position. Fig. 2 is a similar view showing the door-knob bolt in its partially-retracted position, and Fig. 3 is a transverse section on line 3-3 of Fig. 1.

20 The object of my invention is to provide the ordinary door-lock with suitable electric connections whereby upon either the turning 25 of the door-knob or the turning of the key an electric circuit will be closed, the closing of such circuit operating an alarm-bell, which may be located in any convenient part of the house, thereby giving notice of any attempt 30 by unauthorized persons to enter the house.

In detail the invention may be described as follows:

35 Referring to the drawings, C represents the casing of an ordinary lock, B the bolt operated by the turning of the knob K, and B' the bolt operated by the turning of the key.

40 Projecting from the rear wall of the casing C are two binding-posts 1', from which lead wires w w, respectively, to a battery E and an alarm-bell A. The post 1' is carried directly by an insulating-plug 2. To the inner end of the post 1' is secured a circuit-closing spring or contact-strip 3, having an outwardly deflected or bent terminal 3' and an 45 intermediate elbow 3'', the key 4 being adapted to turn between these points and, irrespective of its position, force one or the other of the parts 3' 3'' against the bolt B' or the

metallic casing C, Fig. 2, by which action the circuit is immediately closed and the alarm 50 sounded. So, too, by turning the knob in a direction to retract the bolt B the latter is brought in contact with the adjacent extension of the spring 3, thus again closing the circuit and with the same results. Normally, 55 Fig. 1, the spring 3 is out of contact with any portion of the casing and of course the circuit is open.

It will be observed that with my present invention the burglar may even employ a key 60 made of insulating or non-conducting material, the closing of the circuit being accomplished the moment an attempt is made to turn the key.

I do not, of course, wish to be limited to 65 the details here shown, as these may in a measure be departed from without in any wise affecting the nature or spirit of my invention.

Having described my invention, what I 70 claim is—

1. In a lock, a casing, a knob-actuated bolt, a key-actuated bolt, conducting-wires leading to the casing, a battery and an alarm in the circuit of the wires, and a contact-strip 75 or spring having one end adapted to be forced against the key-actuated bolt or casing, and the opposite end adapted to be brought in contact with the knob-actuated bolt, substantially as set forth. 80

2. In a lock, a metallic casing, a knob-actuated bolt, a key-actuated bolt, conducting-wires, a battery and an alarm in the circuit of the wires, binding-posts carried by the casing and coupled to the wires, an insulating-plug for one of the posts, a contact-strip or spring coupled to the last-mentioned post, one end of the strip having an outwardly deflected terminal and an intermediate elbow adapted respectively upon the turning 90 of the key in proper direction to contact with the key-operated bolt or with the casing, the opposite end of the spring being adapted to contact with the adjacent end of the knob-actuated bolt, the parts operating substantially as and for the purpose set forth. 95

3. In an electric alarm-lock, a contact-strip or spring having one end adapted to be actuated by the key and forced into contact thereby with the bolt, or wall of the casing, and having the opposite end adapted to contact with the knob-actuated bolt, substantially as set forth.

In testimony whereof I affix my signature in presence of two witnesses.

OTTO E. F. HIMMIGHOEFER.
